UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

STITCH-INDENTING MACHINE.

1,165,002.

Specification of Letters Patent. Patented Dec. 21, 1915.

Application filed July 25, 1907, Serial No. 385,454. Renewed October 29, 1915. Serial No. 58,728.

To all whom it may concern:

Be it known that I, EDWARD ERICKSON, of Boston, in the county of Suffolk and State of Massachusetts, have invented certain new and useful Improvements in Stitch-Indenting Machines, of which the following is a specification.

This invention has relation to stitch indenting machines, and has for its object to provide certain improvements therein to simplify the construction thereof and to render them more accurate and efficient in operation.

The manner in which the invention is carried out and in what it consists are set forth in the following specification and claims, and are illustrated upon the accompanying drawings which show one embodiment of the invention.

Referring to said drawings, Figure 1 represents in plan view a stitch indenting machine embodying the invention. Fig. 2 represents a side elevation of the same. Fig. 3 represents a front end elevation thereof. Fig. 4 represents the machine in longitudinal section. Fig. 5 represents a plan view of the machine when the parts have fed and indented the work. Fig. 6 represents a transverse vertical section through the machine on the line 6—6 of Fig. 2. Fig. 7 represents a section on the line 7—7 of Fig. 4.

The machine is provided with the usual supporting standard 10 adapted to rest either upon the floor or a bench as may be required. On the standard is a head comprising a base 11 at the ends of which are the uprights 12, 12, 13, 13. The prime power shaft of the machine, which is indicated at 14, is journaled in bearings in the uprights 12, 12 and is rotated by any suitable means such as a belt pulley 15, the hub 16 of which is illustrated in Fig. 1 as being pinned to said shaft. To the opposite end of the shaft is pinned or otherwise secured a momentum wheel 117 which also affords a means for turning over the machine by hand. In the uprights 13, 13 is journaled a shaft 17 which is adapted to be reciprocated axially or longitudinally. This shaft supports the carrier for the indenting tool which is given a four-way movement to effect the indenting and feeding of the work. To one end of the shaft is attached a lever 18 by means of a screw pin 19 as best shown in Fig. 6. The

other end of the shaft is held against a stop or abutment 20 by a spring 21, one end of which is connected to a pin 22 to one of the uprights 13, and the other end of which is connected to an ear 23 on the end of the lever 18. The said lever 18 is fulcrumed between its ends by a bolt 24 upon a lateral projection 25 on a longitudinal bar 26 which connects the uprights 13 and 12 on one side of the machine. The rear end of the lever 18 carries a roll 27 which is engaged by a face-cam 28 on the hub 16 of the pulley 15. During each revolution of the shaft 14, the lever 18 is oscillated to impart a longitudinal reciprocation to the shaft 17.

The indenting tool is indicated at 29. Its shank is clamped in the end of an arm or carrier 30 and may be adjusted by a screw 31 which is equipped with a lock nut 32. The carrier has a bifurcated hub which is loosely journaled on the shaft 17 but which is held against axial movement relatively thereto by a collar 33 which is straddled by the hub and which is secured to the shaft by any suitable means such as a pin 34 (see Figs. 4 and 6). The carrier 30 is provided with a rearwardly extending arm or lever 35 bearing upon its end a roll 36 which is engaged with a cam 37 secured to the shaft 14. The roll 36 is held against the cam by a spring 35', which will be again referred to in connection with the lock for the work support. The cam 37 and the roll 36 are extended axially sufficiently to prevent their disengagement during the axial movement of the carrier for the indenting tool. The parts are so timed that the indenting tool is first depressed to enter between two stitches and indent the welt of a shoe, then to move laterally to feed the work, then to move upward, and then to move laterally back to its initial position.

For the purpose of holding the work when the indenting tool is disengaged therefrom, I employ a presser-foot which is indicated at 38. This presser-foot has an end adapted to engage the work and is pivoted between its ends upon a bolt 39, which is passed into a bracket 40. The said bracket is supported upon one of the uprights as shown in Fig. 6, and is provided with the depending arm 20 which constitutes the abutment for the shaft 17. The said bracket is adjustable transversely of the machine by means of an adjusting screw 41 passed into

the upright 13 last mentioned, and is secured after adjustment by a screw 42 passed through a slot 43 from said bracket. The adjustment of the bracket varies the length 5 of the reciprocatory movement of the shaft 17 and the lateral movement of the indenting tool, and simultaneously varies the position of the presser-foot. As the position of the presser-foot must be in a certain relation to 10 the initial position of the indenting tool, it will be seen that the adjustment of the bracket 40 preserves this relation. The rear end of the presser-foot 38 is adapted to be depressed or raised to disengage the presser-foot from and engage it with the work. The means by which this is accomplished will be 15 subsequently explained.

The work-support consists of a beveled disk 44, adapted to rotate upon a bearing 45 upon which it is held by a screw 46. This bearing is formed on a member 47 having an ear 48 located in a yoke 49 on a movable support 50. Through the ear and through the yoke is passed a bolt 51, by which they 20 may be clamped rigidly together, but which will permit, when its nut is unscrewed, the work support to be adjusted about a horizontal axis transverse to the machine. The rear portion of the beveled face of the disk 25 lies under the indenting tool 29 and the work is rested thereon as shown in Fig. 4. To resist the thrust of the indenting tool, the member 48 is provided with an arm 52 which extends under the disk immediately 30 35 below the indenting tool to constitute an abutment.

The movable support 50 has a shank 53 which extends downwardly through an aperture in a bracket 54 projecting forwardly 40 from the front uprights 13 and also through a bracket 55 projecting forwardly from the base 11 of the standard 10, as shown in Fig. 2. A spring 56 encircles the shank or spindle, one end engaging the bracket 55 and 45 the other end engaging a collar 57 secured to the shank or spindle. By a suitable treadle mechanism, which is connected with the spindle of the work support, the latter may be depressed against the tension of the 50 spring for the insertion of the work. The treadle mechanism is not shown, as such devices are well known. To assist in guiding the work support in its vertical movements, there is a guide pin 58 projecting upwardly 55 from the bracket 54 through an aperture in the support 50.

I have provided means for locking the work support against depression while the indenting tool is indenting the work. Any 60 suitable locking mechanism may be utilized. I have illustrated upon the drawings, however, a convenient mechanism which serves the purpose. It consists of an elongated lever 59 which is fulcrumed upon a stud 60 65 in the upright 13. The rear end of the

lever carries a roll 61 which is adapted to be intermittently engaged by a cam 62 on the shaft 14. For convenience the two cams 37 and 62 are illustrated as being formed of one piece of metal, but this is not essential. The spring 35', hereinbefore referred to, has one end connected to the carrier arm 35 and its other end to the lever 59 so that these two parts are held yieldingly toward their respective cams. The forward short 70 projecting arm 63 of the lever 59 is provided with an aperture 64 through which the shank 53 of the work support extends. The front and rear of the shank are slabbed off so that in cross section it is substantially 75 elliptical, as illustrated in Fig. 7. The aperture 64 is flaring in opposite directions and its middle portion closely surrounds the shank so that, when the lever 59 is in the position shown in Fig. 4, it frictionally 80 clamps the shank 53 and binds it against movement. When, however, the arm 63 is perpendicular to the shank 53, as shown in Fig. 2, as when the lever 59 is depressed by the cam 62, the shank is free to move 85 through the aperture 64.

The presser-foot 38, previously referred to, is connected to the lever 59 by a connecting rod or link 65 pivoted to each of them, so as to be operated thereby. For the purpose of varying the throw of the presser-foot, its rear end is longitudinally slotted as indicated at 66 to receive a pin 67 which connects the link thereto. As will be explained, when the locking lever 59 is depressed to release the work-support, the presser-foot is raised to permit the feeding of the work by the indenting tool. In order that the work support may be unlocked by hand, a hand lever 68 is fulcrumed by a 90 stud 69 in an ear or lug 70 projecting upwardly from the base of the head. This lever has one arm 71 with a pin or projection 72 which extends over or transversely of the lever 59, so that when the hand lever 95 100 105 110 115 120 125 130 135 140 145 150 155 160 165 170 175 5 moved laterally by a spring 21 a distance equal to a stitch and is depressed again so as to enter between two stitches. The work support remains locked until the indenting tool has reached the downward limit of its movement so as to completely indent the work. The cam 62 then engages the roll 61 on the lever 59 and unlocks the work support and lifts the presser-foot; whereupon 10 the cam 28 moves the lever 18 so as to impel the shaft 17 to the left (looking at the machine from the front) to feed the work, and, during this feeding movement, the work support remains unlocked and the 15 presser-foot remains in its raised position. This completes one cycle of the operation of the machine.

Having thus explained the nature of my 20 said invention, and described a way of constructing and using the same, although without attempting to set forth all of the forms in which it may be made or all of the modes of its use, what I claim is:—

1. In a stitch indenting machine, an indenting tool, a carrier therefor, means for oscillating said carrier to cause the tool to approach and recede from the work, a cam for moving said carrier laterally to feed the work, a spring for moving said carrier laterally in the opposite direction, a presser-foot, means for actuating said presser-foot, and a support for the presser-foot having an abutment for limiting the spring-impelled movement of the carrier, said support being 35 adjustable longitudinally relatively to the said spring-impelled movement.

2. In a stitch indenting machine, an indenting tool, and means for actuating said tool to indent and feed the work, in combination with a work support comprising a spring-supported spindle or shank located below the tool, a bearing member pivoted to the upper end of the shank by a transverse pivot, and having a cylindrical bearing, said 45 member having an arm projecting under the tool, a work-supporting disk rotatable on said cylindrical bearing with its under face near its periphery slidingly engaging the end of the said arm, and means for locking the spindle against yielding movement when the tool is depressed to indent and feed the work.

3. In a stitch indenting machine, an indenting tool, means for actuating said tool to indent and feed the work, a presser-foot, a spring-tensioned work support, a lock for the work support to resist movement thereof, means for actuating said lock to release the work support, and means operative by 55 said lock-actuating means for actuating the presser-foot.

4. In a stitch indenting machine, a shaft, an indenting tool, means actuated by said shaft for periodically depressing said tool 60 to indent the work, a presser-foot, a spring-

tensioned work support, a shank for said work support, a pivoted locking lever having oppositely disposed faces adapted to engage the said shank for locking and releasing it as said lever is moved about its pivot, and means actuated by said shaft for actuating said lever to lock said shank against movement when the indenting tool is depressed to indent the work.

5. In a stitch-indenting machine, an indenting tool, a movable work support, a movable member for actuating said tool, a movable member for locking said work support, a power shaft having cams for operating said tool-actuating member and locking 75 member respectively, and a spring connecting said tool-actuating member and locking member whereby the indenting tool is retracted and the work support is locked.

6. In a stitch indenting machine, an indenting and feeding tool, a shaft, means actuated by said shaft to intermittently depress said tool to indent the work, a de-pressible work support having a shank or 85 spindle, a locking lever having oppositely disposed faces adapted to engage and bind the shank or spindle against movement when the lever and shank are at an angle other than a right angle, and means for intermittently actuating said lever to bind the 90 spindle as the tool is depressed and to release the spindle when the tool is raised.

7. In a stitch-indenting machine, means for alternately indenting and feeding the work, a yielding work support, means for locking 100 the work support at the completion of each feeding operation, said means prolonging the locking until the completion of the next indenting operation and releasing the work support prior to the next feeding operation, 105 a yielding presser-foot for clamping the work against the work-support, and means connecting said locking means and presser-foot whereby the presser-foot is retracted when the work support is unlocked.

8. In a stitch-indenting machine, a movable work support, a presser-foot, yielding means for causing them to clamp and hold the work, means for indenting the work and feeding the same step by step, means for locking the work support to sustain the pressure thereon by said indenting and feeding means during the indenting operation thereof, and means for actuating said locking means and presser-foot at the finish of the 115 indenting operation to release the work support and retract the presser-foot prior to the feeding operation.

9. In a stitch-indenting machine, a movable work support, a presser-foot, yielding 120 means for causing them to clamp and hold the work, means for indenting the work and feeding the same step by step, means for locking the work support to sustain the pressure thereon by said indenting and feed- 125

85 85 to indent the work, a presser-foot, a spring-

ing means during the indenting operation thereof, means for actuating said locking means at the finish of the indenting operation and prior to the feeding operation to release the work support, and means for retracting the presser-foot at the finish of the indenting operation and prior to the feeding operation.

In testimony whereof I have affixed my signature, in presence of two witnesses.

EDWARD ERICKSON.
